OPERATING MECHANISM FOR NEEDLE THREADING DEVICES

Hermann Zink and Herbert Wenz, Kaiserslautern, Germany, assignors to G. M. Pfaff A.-G., Kaiserslautern, Germany

Application March 31, 1954, Serial No. 420,169

Claims priority, application Germany April 9, 1953

4 Claims. (Cl. 112—225)

The subject of the invention is an improvement and further development of the operating means for needle threading devices of the type mounted in the head of a sewing machine. The operating means in accordance with the present invention are especially adapted for threading devices for machines including a needle bar oscillator operatively cooperating with the needle bar to cause movement of the needle bar.

In devices of this type for example as shown in U. S. application No. 335,723 of February 9, 1953, Patent No. 2,727,479 dated December 20, 1955, a bar carrying the threading hook is mounted on the machine arm or in the needle bar oscillator in bearings arranged parallel to the needle bar. Cooperating with a sliding member having a curved track and a spring arrangement, an operative relationship is automatically established between the guide bar for the threading device and the needle bar for alignment of the threading device with the eye of the needle. Furthermore, axial movement and rotation of the guide bar is effected. The sliding member is provided for operation with an operating lever downward movement of which causes the threading device to swing into the eye of the needle. The sliding member can be guided by means of a lug or the like in a plate on the head of the machine. In one arrangement the operating lever which is formed as a unitary structure with the sliding member extends forward through a slot out of the housing if the guide bar is arranged at the head of the machine, while it extends through a corresponding opening at the lower part of the head, if the guide bar is mounted on the needle bar oscillator and it is provided on an axial extension of the sliding member. In that case the handle is horizontally disposed. One part of the spring arrangement which cannot be accommodated in the housing thus remains exposed and visible exactly in the line of vision of the operator upon the sewing area.

In connection with this latter arrangement it has proven to be advantageous to have a member constitute the manipulating lever which is not a downwardly extending part of the slide as is the lever 20 in the arrangement illustrated in said application No. 335,723. The manipulating lever which projects from the lower end of the head on the one hand necessitates prolongation of the hook carrier, while on the other hand it moves back and forth with the needle bar during zig-zag stitching operations, a matter which is found to be annoying to the operator in the observation of the stitches. In the aforementioned arrangement a long slot in the head of the machine does not only adversely affect the appearance of the closed head conformation which is a desideratum, but it offers an entrance possibility for dust. Moreover, it is more advantageous to locate the manipulating lever for gripping to the rear of the machine head. Finally, a manipulating lever which is not rigidly connected with the threading means can be arranged in such a manner that owing to a gearing relationship the slot through which it extends from the housing can be much smaller than is the case

2

where direct operation is provided, i. e. where the manipulating lever is formed as a unitary structure with the sliding member.

The present invention solves the aforementioned problem with an operating arrangement where essentially the manipulating lever is a two armed lever which is separated from the sliding member, the pivot bolt of which lever is mounted on the head plate of the machine which covers the front opening. The possibility of separating the threading device from the manipulating or operating device which is thus afforded and the accurately guided interengagement of both during the mounting of the head plate is insured by a long slot provided in the end of the operating lever which is disposed opposite from the gripping handle. As to the threading device proper, a stud is provided on its sliding member which extends into the slot on the manipulating lever when the head plate is in place. Furthermore, there is located on the sliding member, parallel to the stud, a lug or the like which is guided in a vertical conformation on the head plate and prevents lateral turning of the threading device which would otherwise be possible with the new and non-rigid coupling between the manipulating lever and the sliding member defined by the engagement of the stud with the slot.

In accordance with the invention the operating lever is biased in non-operative direction by a spring which is supported on the head plate and which takes over a part of the functions which in older devices, such as referred to above are performed by the special spring system for the threading device, such as, for example, a spring disposed around the vertical bar which supports the threading hook.

The arrangement of the manipulating lever in accordance with the invention is possible in connection with both, threading hook guiding bars mounted in the head and also with such bars supported in the oscillator bar such as shown in said application Ser. No. 335,723.

An embodiment in accordance with the present invention is illustrated in the drawing in connection with a guiding bar arrangement in the oscillator bar.

Fig. 1 is a perspective illustration of the threading device disposed in the machine head and of the components of the manipulating device located in the head plate;

Fig. 2 is a perspective view of the manipulating or operating lever;

Figs. 3, 4 and 5 illustrate in a front, a side and a top view the manner of controlling the movement of the guide bar by means of a ring which is adjustable on the needle bar.

The needle bar oscillator 1 of the machine carries the threading device comprising primarily the guiding bar 2, the clamp member 3 which has secured to it at its lower end the threading hook which enters the eye of the needle during operation and the sliding member 4. Sliding member 4 supports a stud 5 and presents an angularly projecting lug 6 cut and bent out of the material of said member. The head plate 7 pivotally supports a two armed operating lever 8 secured thereto by means of a screw 9 constituting a pivot bolt.

A spring 10 is secured at one end in a circular groove 11 on a stud in the head plate 7 and at the other end to a bore 12 in the operating lever 8. A slot 13 is defined in one end of the operating lever to receive the stud 5 while the other end of the lever is formed into a handle 14 projecting rearwardly from head plate 7.

Two ribs 16 projecting from the head plate 7 define a guiding groove for the lug 6. The springs 10 and 17 constitute parts of the spring system for operation of the threading device guiding bar 2 which is thus entirely encased in the head of the machine whereas in devices

of the prior art one of the springs was exposed on the bar 2 between the clamp member 3 and the lower bearing 18 of the threading device while another spring is located on the bar 2 in engagement with the sliding member 4.

These springs are now replaced in a novel and more expedient manner by spring 17 which is anchored to lug 6 and to a pin 15 which projects through the guiding bar 2 and guide slot 19 of the sliding member 4. The lower spring which was exposed and disposed around the bar is now represented by spring 10.

Moving handle 14 of the lever 8 upwardly while stud 5 rests in slot 13 causes downward movement of the slide 4 and bar 2 while spring 10 is expanded until the hook arm carried by clamp 3 is horizontally aligned with the eye of the needle of the machine. At that point the downward movement of the bar 2 is stopped, for example, by the other end of the pin in slot 19 striking a flat horizontal abutment 65 on a member 64 which is mounted on the needle bar 61 on which it is adjustable by means of set screws 62 and 63. The pin 15, being guided in the slot 19 rotates the bar and swings the pointed end of the hook arm into engagement with the needle eye. During the phase of the movement of the sliding member when the downward movement of the guiding bar 2 has ceased, the sliding member continues to move while the spring 17 is also expanded.

The movement of guided bar 2, relative to the needle bar will be understood best if reference is had to Figs. 3, 4 and 5, explaining this subject matter as originally disclosed and described in Ser. No. 305,674, owned by the same assignee.

The spring 17 holds the pin 15 in the lowermost position in the slot 19 during downward movement of the sliding member 4. As soon as the pin 15 engages the horizontal abutment 65 the downward movement of the guiding bar 2 stops, while the sliding member 4 continues to move, thus guiding pin 15 in slot 19 and rotating bar 2.

Releasing the pressure on the handle 14 first results in the spring 17 contracting and bar 2 moving back into normal angular position while being guided by the pin 15 in slot 19. Spring 10 exerts pulling pressure on sliding member 4 by way of stud 5 and moves the sliding member upwardly while bar 2 is rotated back to normal axial position by pin 15 which is held on abutment 65 by spring 17 until the end of pin 15 is engaged by the lower end of slot 19. Upon return of the bar 2 to normal axial position the continued pull of spring 10 on the lever 8 returns the sliding member and the guide bar 2 to the normal position illustrated in the drawing by moving them vertically and upwardly.

Having now described the invention with reference to the embodiment shown, we do not wish to be limited thereto, but what we desire to protect by Letters Patent is set forth in the appended claims.

We claim:

1. Operating means for a needle threading mechanism of the type including a guiding bar disposed parallel to the needle bar in the head of a sewing machine and supporting a hook arm rotatable in a horizontal plane for engagement with the eye of the needle, and a sliding member in engagement with said guiding member and having operative engagement with said operating means; said means including a lever pivotally supported in the head of the machine having one end presenting a handle extending outwardly through a slot in the head of the machine and one end provided with an operating slot, a first spring extending between said lever and a fixed point in the head of the machine for maintaining said lever in inoperative position, a guiding groove in the head of the machine, a stud carried by said sliding member and extending into said operating slot for operation of said sliding member and the guiding bar in response to movement of said lever, a lug projecting from said sliding member into said guiding groove to guide said sliding

member, and a second spring extending between anchoring points on said sliding member and said guiding bar capable of biasing said sliding member to inoperative position on the guiding bar.

2. Operating means for a needle threading mechanism of the type including a guiding bar disposed parallel to the needle bar in the head of a sewing machine and supporting a hook arm rotatable in a horizontal plane for engagement with the eye of the needle, and a sliding member in engagement with said guiding member and having operative engagement with said operating means; said means including a lever pivotally supported in the head of the machine having one end presenting a handle extending outwardly through a slot in the head of the machine and one end provided with an operating slot, a first spring extending between said lever and a fixed point in the head of the machine for maintaining said lever in inoperative position, a guiding groove in the head of the machine, a stud carried by said sliding member and extending into said operating slot for operation of said sliding member and the guiding bar in response to movement of said lever, a lug projecting from said sliding member into said guiding groove to guide said sliding member, and a second spring extending between anchoring points on said sliding member and said guiding bar capable of biasing said sliding member to inoperative position on the guiding bar, said guiding groove extending in said head plate substantially parallel to said guiding bar.

3. Operating means for a needle threading mechanism of the type including a guiding bar disposed parallel to the needle bar in the head of a sewing machine and supporting a hook arm rotatable in a horizontal plane for engagement with the eye of the needle, and a sliding member in engagement with said guiding member and having operative engagement with said operating means; said means including a lever pivotally supported in the head of the machine having one end presenting a handle extending outwardly through a slot in the head of the machine and one end provided with an operating slot, a first spring extending between said lever and a fixed point in the head of the machine for maintaining said lever in inoperative position, a guiding groove in the head of the machine, a stud carried by said sliding member and extending into said operating slot for operation of said sliding member and the guiding bar in response to movement of said lever, a lug projecting from said sliding member into said guiding groove to guide said sliding member, and a second spring extending between anchoring points on said sliding member and said guiding bar capable of biasing said sliding member to inoperative position on the guiding bar, said guiding groove extending in said head plate substantially parallel to said guiding bar, and said first spring being secured at one end to said lever and at the other end to a pivot on the head plate and being adapted to apply pressure to said stud on said sliding member by way of said operating slot.

4. Operating means for a needle threading mechanism of the type including a guiding bar disposed parallel to the needle bar in the head of a sewing machine and supporting a hook arm rotatable in a horizontal plane for engagement with the eye of the needle, and a sliding member in engagement with said guiding member and having operative engagement with said operating means; said means including a lever pivotally supported in the head of the machine having one end presenting a handle extending outwardly through a slot in the head of the machine and one end provided with an operating slot, a first spring extending between said lever and a fixed point in the head of the machine for maintaining said lever in inoperative position, a guiding groove in the head of the machine, a stud carried by said sliding member and extending into said operating slot for operation of said sliding member and the guiding bar in response to movement of said lever, a lug projecting from said sliding member into said guiding groove to guide said sliding

member, and a second spring extending between anchoring points on said sliding member and said guiding bar capable of biasing said sliding member to inoperative position on the guiding bar, said guiding groove extending in said head plate substantially parallel to said guiding bar, and said first spring being secured at one end to said lever and at the other end to a pivot on the head plate and being adapted to apply pressure to said stud on said sliding member by way of said operating slot, and

said second spring having one end secured to said lug and the other end to a member extending from said guiding bar through a slot in said sliding member.
